UNITED STATES PATENT OFFICE

ELMER J. BLISS, OF BOSTON, MASSACHUSETTS, ASSIGNOR TO REGAL SHOE COMPANY, OF WHITMAN, MASSACHUSETTS, A CORPORATION OF MASSACHUSETTS

DEVICE FOR MEASURING CUBIC CAPACITY OF SHOES

Application filed August 31, 1929. Serial No. 389,676.

This invention relates to the measurement of shoes and is intended to provide a device by means of which the cubical content of the forepart of a shoe may be accurately ascertained, both for the purpose of determining whether the forepart of any given shoe has a correct internal capacity or foot-receiving space and also as an aid to the correct designing of lasts for the making of shoes.

With these objects in view the invention comprises essentially a skeleton frame of definite and known size provided with an elastic wall of material that is impervious to water, which forms a sac or pouch conforming normally to the shape of a shoe forepart and capable, when inserted in a shoe to be tested, of being expanded by the pressure of liquid introduced therein into close contact with the surrounding portion of the shoe upper. The volume of liquid, which the expanded or extended foot form is capable of receiving, will measure the cubic content of that part of the shoe. This and other features of the invention will be explained in the following specification and will be defined in the claims hereinafter annexed.

In the accompanying drawing I have illustrated a simple and convenient form of construction and arrangement embodying the principles of this invention, in which

Fig. 1 is a longitudinal vertical section showing the expansible foot form and its associated appliances.

Fig. 2 is a plan view of the same, the heel block being omitted.

In the practice of this invention according to the form illustrated in the drawing, I provide a front member or toe block 2 adapted to occupy the contracted toe portion of a shoe at a definite size distance from the heel of the shoe and from the ball location thereof.

The rear member of the skeleton frame comprises a transverse wall block 1 which is shaped and dimensioned to fit into the transverse plane of a standard shoe of given length-size and having the narrowest width in which such length-sizes are usually made. The front and rear members are rigidly secured together by means of a bar 3 provided with a front-attaching flange 2^a and a rear-

attaching flange 1^a spaced the proper distance apart to bring the toe block and the rear wall into proper spaced relation for a shoe of predetermined size length. The toe block fills out what is known as the extension space, that is, that portion of the toe of a shoe that extends beyond the tip of the toe of a foot for which the shoe is designed.

The distensible wall of the measuring device comprises a sheet 8 of elastic material, such as rubber, that is impervious to water and which is shaped to conform normally, when not under internal pressure, to the interior contours of a shoe of given length having the narrowest standardized width. Preferably the forward member, or toe block, 2 is inserted inside this elastic foot form or pouch and an encircling band 8^b is tightly passed around the periphery near the rear edge of said block to act as an anchorage for binding the elastic sheet securely around this portion of the block and also to protect this portion of the elastic sheet from undue rubbing against the corresponding part of the shoe when it is inserted therein.

The rear end of the elastic pouch or foot form 8 is drawn over the periphery of the rear member 1 and is tightly secured thereto by an encircling band 8^c.

As it is important that the measuring device shall have a predetermined length corresponding to a definite length-size of shoe so that the rear member will be positioned a definite distance from the heel or counter of the shoe, I provide two toggle levers 10 and 12 connected together by a pivotal bolt 11, the forward member 10 of which is secured to a bail-like extension 12 whose arms are pivotally connected with angle brackets 13 secured to the rear end of the frame member 1. A heel block 14 is secured to the rear end of the rear toggle 12 to form an abutment against the inside of the counter or heel portion of the shoe. The device may be adapted for more than one length of shoe by providing a plurality of pivot holes 11^a to form an adjustable connection between the two toggle elements. A thumb piece 10^a, formed by a transversely bent lug on the link 10, serves

as a convenient means for pressing down the toggle links to normal extension position.

To introduce liquid into the hollow foot form or measuring chamber there is provided an inlet passage 3^a which, in this case, is formed by boring out the rear end portion of the frame bar 3 and providing that bore with an inlet port 3^b through which liquid introduced through the hollow extension 3^a enters the distensible foot form. For further convenience a valve fitting 6 is secured to the rear end of the filling nipple 3^a and in this valve nipple is placed a two-way rotatable valve 7 which has a nippled connection 6^a with a hose 6^b which supplies liquid under a definite known pressure to the interior of the hollow foot form, thereby causing the elastic wall 8 to be distended until it completely fills out the forepart of the shoe, that is, the portion included between the rear of the toe block and the front wall of the rear member 1. To prevent leakage of liquid, as well as to secure the rear wall rigidly to the bar 3 which forms the backbone of the frame, a clamping nut 5 is placed on the end of the nipple member 3^a with an interposed gasket. To allow the escape of air from the interior of the foot form while the liquid is being introduced, a vent opening is provided in the upper portion of this wall normally closed by a sealing plug or valve 9.

Let us suppose that it is desired to test the cubical contents of a No. 7 shoe. The appropriate length of foot form will be inserted in the shoe and pushed forward by straightening the toggle, which will result in locating the rear member 1 a definite distance from the rear of the ball or widest portion of the shoe. The vent orifice plug 9 is removed, the valve 7 is opened and the liquid is allowed to flow in under pressure to completely fill and expand the hollow foot form. As soon as water begins to issue from the vent orifice that is closed by insertion of the plug and the liquid under pressure serves to expand the distensible wall 8 into full contact with the interior of the forepart. The valve 7 is then closed and the device is removed from the shoe. Thereafter by withdrawing the vent plug the valve may be turned to discharge the water from the measuring chamber and the water, thus discharged, can be measured in a graduated glass or may be weighed to determine exactly the volume of liquid that was introduced into the foot form to cause it to completely fill the forepart.

Of course, in the calculation the displacement of the rod 3, as well as the thickness of the elastic wall, will be taken into account, but as these would have known bulk when the device was made their known capacity added to the volume of liquid withdrawn would give with practical precision a vol-

ume measurement of the forepart of the shoe being tested.

What I claim is:

1. A device for measuring the cubic capacity of the forepart of a shoe embracing in its construction a frame comprising front and rear members adapted to be inserted into the forepart of a shoe, and a wall of elastic material secured around said frame to form a hollow expandible chamber capable of expanding into conformity with the surrounding portion of the shoe, and means for introducing a liquid therein to expand the elastic wall against the confining portion of the shoe. 70 75 80

2. A device for measuring the forepart capacity of a shoe embracing in its construction a measuring chamber comprising fixedly related front and rear walls and a peripheral wall of elastic material secured to said front and rear walls and conforming approximately in contour to the interior of the forepart of a shoe, the rear wall being provided with a valve inlet for the introduction of liquid under pressure whereby the peripheral elastic wall may be expanded into conformity with the surrounding portion of the shoe. 85 90 95

3. A device of the class described embracing a hollow, peripherally expandible, liquid measuring chamber of predetermined fixed length, means for introducing liquid under pressure into said chamber to expand its peripheral portion into conformity with the interior of the surrounding portion of the shoe without varying the length of the chamber, 100 and heel-engaging positioning means secured to the rear wall of said chamber in order to locate the rear wall at a predetermined distance from the heel. 105

4. A device of the class described embracing a hollow chamber of fixed length having a peripheral wall of distensible material, positioning means secured to the rear portion of said chamber and embracing pivotally connected toggle links, the rear one of which is provided with a heel-engaging member which acts to position the hollow chamber in the shoe when the toggle links are in extended position, and means for introducing a measurable quantity of liquid under pressure to 110 the interior of said chamber. 115

5. In a device of the class described, a hollow foot form embracing front and rear members and an interior connecting bar for securing them together a predetermined distance apart, an elastic peripheral wall connecting said two members to form a closed distensible chamber, said bar being provided with an inlet passage for supplying liquid thereto under pressure, the rear member being provided with a vent orifice that is provided with a sealing closure. 120 125

6. A device for measuring the cubic capacity of the forepart of a shoe embracing in its construction, a toe piece adapted to fit 130

into the tip of the toe of a shoe, a transverse rear wall conforming approximately to the cross sectional contour of the shoe at the rear of the ball portion, means for securing the 5 toe piece and the rear wall in fixed spaced relation, an elastic peripheral wall whose front and rear end portions are tightly secured to the toe piece and the rear wall to form a chamber conforming approximately to that 10 portion of the interior of the shoe that subtends the space between said toe piece and rear wall, and means for introducing a measurable quantity of liquid into the measuring chamber according to the permissible distension 15 of the elastic wall by the liquid to ascertain the cubic capacity of said chamber when the elastic wall is in contact with the subtending portion of the shoe.

In witness whereof, I have subscribed the 20 above specification.
